UNITED STATES PATENT OFFICE.

WILLIAM P. HORTON, JR., AND ANSEL B. JONES, OF CLEVELAND, OHIO; SAID
HORTON ASSIGNOR TO WILLIAM P. HORTON, OF SAME PLACE.

METHOD OF AND APPARATUS FOR OBTUNDING NERVES.

SPECIFICATION forming part of Letters Patent No. 535,905; dated March 19, 1895.

Application filed March 31, 1893. Serial No. 468,591. (No model.)

To all whom it may concern:

Be it known that we, WILLIAM P. HORTON, Jr., and ANSEL B. JONES, citizens of the United States, residing at Cleveland, in the county of Cuyahoga and State of Ohio, have invented a Method of and Apparatus for Obtunding the Sensory Nerves of the Teeth During the Excavation of Cavities; and we do hereby declare the following to be a full, clear, and exact description of the invention, such as will enable others skilled in the art to which it appertains to make and use the same.

Our invention relates to a process of obtunding the sensory nerves of a tooth during the excavation thereof, and it consists in the following steps: first, in applying to that side of the patient's face on which the tooth to be excavated is located, an electrode which is connected with one pole of an electrical generator; second, in connecting the excavating instrument with the other pole of said generator; third, in varying the external resistance in the circuit during the operation, substantially as hereinafter described.

25 The drawing represents the apparatus for carrying our process into effect, applied in the manner hereinafter described.

In carrying out our process, we commonly employ the current generated by a single cell 30 battery, but we have in our experiments and operations, found cases where the current from as many as four cells was necessary. An electrode A, connected with one pole of the generator B, (preferably the negative pole) 35 is secured by means of a rubber strap a, or by any suitable means, to that side of the patient's face on which the tooth to be excavated is located. The other pole of the generator is electrically connected with the excavating 40 instrument C. In the modern practice of dentistry, the excavator is generally a revoluble burr driven by a dental engine. Care must be exercised to compel the passage of the current from the excavator to the electrode 45 A through the tooth. To secure this result, it is best to form the hand piece of the excavator of some insulating material; and the excavator should be so used that there is no electrical connection between it and any 50 other part of the patient than the tooth.

The reason for preferring to connect the

electrode A with the negative pole is as follows: One source of the pain experienced by the patient is due to the laceration of the nerve filaments in the tubuli which ramify 5 in the dentine. Another source of pain is the heat generated by the revolution of the burr. Now, it is found that in passing an electrical current through the human body, heat is generated at the negative electrode. Therefore, 60 in order that the pain due to the heat generated necessarily by the burr shall not be increased by the heat due to the electric current, we prefer to connect the electrode A with the negative pole as stated.

The teeth are supplied by nerves which originate in the fifth cranial nerve. Branches of the fifth nerve of the cranium pass from the cranial cavity through channels in the superior or sub-maxillary bones; and being 70 sub-divided, enter the several teeth, wherein they are again sub-divided, forming the minute nerve filaments which ramify the dentine. The parts of the nerve in the teeth and in the channels in the bone, are therefore more or less completely insulated (electrically) 75 from each other, as well as from other parts of the anatomy; so that a current of electricity introduced into a tooth, must pass with comparatively little loss over the nerves as 80 conductors into the cranial cavity. The shortest route for the escape of the current therefrom, is through the foramina in the skull, through which pass other branches of the fifth nerve to supply the face. In order, therefore, 85 to pass over the sensory nerves of a tooth, an electrical current which will meet with as little resistance from the body as possible, we place one electrode as before stated, against the side of the face just in front of the lower 90 lobe of the ear. By placing the electrode here, there is not only the least possible resistance in the body, but there is also the least variation in the resistance in different patients.

Our theory with respect to the process is 95 substantially as follows, viz: that in any given individual, it is necessary to pass over each of the filaments which are affected by the operation, some certain quantity of current. We are unable to express in the terms employed in electrical measurement, what quantity 100 of current is required, for several reasons,

viz: first, we have been unable to measure the entire quantity which passes through a patient by any instrument which we have been able to obtain; second, it is impossible to determine how much the current is sub-divided in its passage through the dental filaments; that is to say, to determine what part of the entire quantity employed passes over any one filament. This quantity, moreover, differs 5 in different individuals, this difference being apparently dependent on differences in what, in common parlance, is known as the sensitiveness of the nerves. Perhaps a more accurate statement of the causes of these differences is this, viz: that the teeth of some persons contain more nerve filaments than others, which filaments are placed more closely together. Another cause of the personal differences may be the fact, that owing 10 to differences in the structure of the teeth and bones, the nerves are more completely insulated electrically in some persons than in others. Now, it is possible that the theory above outlined may be incorrect, but we have 15 found it entirely consistent with the acts necessary to be done in order to be practically successful in excavating teeth by the described process without pain.

In order to vary the quantity of current to 20 compensate for the varying conditions which arise in practice, it is necessary to connect into the circuit a resistance box by means of which the operator may vary the external resistance, that is to say, the resistance external to the body. We have found in practice 25 that a resistance box, capable of introducing about fourteen thousand ohms resistance, by increments of one hundred ohms, is a suitable box for the purpose. In the drawing, this 30 resistance box is represented by D. It is unnecessary to describe in detail the construction of the box. It is provided with two switches, d and d', which are adapted to engage with any one of the contact points, 1, 2, 35 3, &c., and 13, 14, &c., respectively. When switch d touches the contact point 1 and switch d' touches contact point 13, the box 40 introduces into the circuit approximately fourteen thousand ohms resistance. As the 45 switch is moved up into contact successively with the contact points 2, 3, 4, &c., the resistance is reduced approximately one thousand ohms for each point. When the switch d' is moved successively into contact with the 50 points 14, 15, &c., the resistance is reduced approximately one hundred ohms for each point.

As before stated, the quantity of current required differs in different individuals, and it also differs in different teeth of the same 55 person, and even at different periods in the excavation of the same tooth.

In conducting operations according to the process, we prefer to begin an operation when the switches d and d' are in engagement with 60 the points 1 and 13,—that is to say, with as much resistance in the circuit as can be in-

troduced by the box, and with a current generated by one cell of a Leclanché battery or its equivalent. If the resultant quantity is sufficient,—and it is impossible to predetermine this because of the personal idiosyncrasies,—the patient feels no sensation from the dental nerves. As for example, when one's hand is not being touched by any external object, there should be no sensation therein. 70 If the quantity of current is insufficient, the patient will feel a sensation in the dental nerves affected by the revolution of the burr. The first sensation will not, if the operator is watchful and careful, be one of pain. It will 75 resemble the sensation produced by touching an external object to the hand. The operator now reduces the resistance by the movement of the switch d from point 1 to points 2 or 3 and so on, trying the current carefully 80 after each movement, until the operation may be proceeded with without producing any sensation in the dental nerves. To attain this result, it may be necessary to move the switch d' by which the resistance may be 85 changed by increments of one hundred ohms. It is not necessary to proceed in the described manner in each case, but we prefer it because there is then comparatively little danger thereby of employing too strong a current, 90 which might injure the nerve, or might produce even greater pain than would result from the excavation of the cavity without any current.

The operator may be guided in the practice 95 of the process as above set forth, or in proceeding more directly in the application of the proper quantity in any case by the following facts: In removing what is commonly called white decay, a less quantity of current 100 is needed than in any other operation,—because the decayed matter is soft, whereby little heat is developed by the revolution of the burr, and further, because the burr does not come in direct contact with any live filament. In removing the so-called leathery 105 tissue, a greater quantity of current is required, for the reason that the under side of this leathery patch enters numerous tubuli in the tooth, whereby all the filaments in said 110 tubuli are affected more or less by the working of the burr in said tissue. When all of the decayed substance has been removed, and the burr is acting on the healthy dentine, either 115 for the purpose of thoroughly cleansing the cavity, or for drilling the retaining points for the filling, a still greater quantity of current 120 is required. In drilling into the dentine, it is found that the quantity of current required is greater as the said dentine is harder, because more heat is generated by the revolution of the burr in hard dentine than in soft dentine. Care must be taken to prevent the burr from touching any other part of the tooth than that at which the drilling is in 125 progress, because by such touching a part of the current is divided from the filaments 130

which are being lacerated or otherwise affected by the operation. If, however, the cavity is so situated that to excavate it, it is impossible to avoid touching the side walls, the quantity of current must be increased.

In operating under the different conditions named, we have found that, in the average case, white decay may be removed without pain to the patient by the use as described, of a quantity of electricity which results from the employment of a single cell and the introduction of approximately ten thousand ohms external resistance into the circuit; to remove leathery tissue, a quantity of electricity which results from one cell and the introduction of approximately seven thousand ohms external resistance. For drilling into the healthy dentine, a current having the same electro-motive force and approximately four thousand ohms resistance will often produce the desired result. It will be understood that these figures are only approximate. The very great differences in personal characteristics render a more exact statement impossible. We have heretofore recommended that a current of small quantity be employed at the beginning of an operation, and that the quantity be gradually increased by reducing the resistance, until it is sufficient. The above figures may guide the operator by informing him of the points at which he may ordinarily expect to be successful. It sometimes happens, however, that a less quantity will be sufficient. It sometimes, though seldom, happens that an electro-motive force of two, three or even four cells will be required.

The essential feature of the discovery is this, viz: that if one electrode be placed against one side of the patient's face on which a tooth is located, said tooth may be excavated without pain to the patient if the proper quantity of an electric current is passed into said tooth from the excavating instrument. The foregoing directions are merely suggestions, as explicit as the nature of the case will permit, as to the best method of determining the proper quantity of current required.

We are aware that attempts have heretofore been made to obtund the nerves of a tooth during the excavation thereof, by means of an electrical current. We are aware also of the Patent No. 22,851, granted February 8, 1859, to W. G. A. Bonwell, which describes a method and apparatus having for their object this result; but we do not intend that our claim shall include the process described by Bonwell. Bonwell suggests that one electrode be held in one hand. We have tried this method, but have been unable to secure any satisfactory results. To be successful, we find it necessary to apply one electrode to that side of the face on which the tooth is located. This makes it possible to send over the dental

nerves the proper quantity of current of an intensity not too great to be effective.

Bonwell suggests that the power of the current be graduated so as to be just strong enough. This statement begs the question, for it gives no information as to the manner in which the current should be graduated nor as to the principles which should govern in graduating it. We have discovered and hereinbefore described what quantity of current approximately is required, and the principles which should govern the operator in changing the external resistance in the current so that the desired result shall be obtained under the varying conditions which arise in practical work. We intend that our claims shall be limited to include the doing of those things the necessity for which we have discovered.

Having described our invention, we claim—

1. The herein described process of obtunding the sensory nerves of a tooth during the excavation of a dental cavity therein, which consists in (first) applying to that side of the patient's face on which the tooth is located, an electrode which is connected with one pole of an electrical generator, (second) connecting the excavating instrument with the other pole of said generator; and (third) varying the current outside the body of the patient, substantially as and for the purpose specified.

2. The herein described process of obtunding dental nerves during the excavation of a tooth, which consists in (first) applying to that side of the patient's face on which the tooth to be excavated is located, an electrode which is connected with the negative pole of a galvanic battery; (second) connecting the excavating instrument with the positive pole of said generator; and (third) varying the resistance in the circuit outside of the patient during the progress of the excavating operation, substantially as and for the purpose specified.

3. In an apparatus for excavating dental cavities and simultaneously obtunding the sensory nerves which are being affected by the operation, the combination of an electrical generator, an electrode connected with one pole of said electric generator, and means for securing the same against the patient's face, with the revolving burr of a dental engine having an insulating hand piece, suitable electrical connections between said burr and the other pole of said battery, and means for varying the resistance in the circuit by small increments, substantially as and for the purpose specified.

In testimony whereof we affix our signatures in presence of two witnesses.
